UNITED STATES PATENT OFFICE.

ABRAM L. COVEY, OF ST. PAUL, NEBRASKA.

PLOW.

No. 891,913.

Specification of Letters Patent.

Patented June 30, 1908.

Original application filed August 6, 1907, Serial No. 387,352. Divided and this application filed October 17, 1907.
Serial No. 397,853.

To all whom it may concern:

Be it known that I, ABRAM L. COVEY, citizen of the United States, residing at St. Paul, in the county of Howard and State of Nebraska, have invented certain new and useful Improvements in Plows, of which the following is a specification.

The present invention contemplates certain new and useful improvements in plows 10 and relates more particularly to a mold board construction embodying novel means whereby the mold board can be properly adjusted so as to turn the furrow slice in the most effective manner when operating in 15 connection with various types of soils.

To this end the invention resides principally in the provision of a mold board embodying a yielding extension, and novel means for holding the said yielding extension in an ad- 20 justed position.

The present case is a divisional application of a case filed August 6th, 1907, Serial No. 387,352.

For a full description of the invention and 25 the merits thereof and also to acquire a knowledge of the details of construction and the means for effecting the result, reference is to be had to the following description and accompanying drawings, in which:

30 Figure 1 is a perspective view of a plow having the improved mold board applied thereto. Fig. 2 is a detail view of the mold board extension detached together with the braces for holding the same in an adjusted 35 position. Fig. 3 is a similar view showing the opposite side of the mold board extension.

Corresponding and like parts are referred to in the following description and indicated in all the views of the drawings by the same 40 reference characters.

Referring to the drawings the numeral 1 designates the land side of the plow and 2 the handles thereof, the said members being of any approved construction. The mold board 45 comprises in the present instance a lower section 3, and an upper section 4, the rear edge of the latter section inclining upwardly and the lower section 3 projecting beyond the upper section. The mold board extension is

50 in the nature of a yielding or spring strip 5 extending upwardly approximately parallel

to the upwardly inclined rear edge of the upper section 4 of the mold board and secured to the rearwardly projecting portion of the lower section 3 of the mold board. For the 55 purpose of holding the extension 5 in an adjusted position a rod 6 is utilized, one end of the rod being secured to the upper end of the spring extension 5 while the opposite end is secured to some rigid portion of the plow 60 such as the land side 1. This rod 6 is extensible and is formed in two sections having their inner ends oppositely threaded and engaged by a sleeve 7. With this construction it will be readily apparent that by turning 65 the sleeve 7 the mold board extension 5 can be drawn inwardly or sprung outwardly and set at the required angle for turning the furrow slice in the most effective manner. A brace member 8 connects an intermediate 70 portion of the rod 6 to the mold board and serves to lock the said rod 6 against bending or vibration. It will be observed that the brace 8 is also extensible and comprises two sections having the inner ends thereof op- 75 positely threaded and received by a sleeve 9 similar to the before mentioned sleeve 7, one end of said brace being formed with an eye by which it may be slipped over the rod 6, after the sections of said rod are disconnected 80 from each other, as indicated in Fig. 3.

Having thus described the invention, what is claimed as new is:

A plow embodying a mold board, an adjustable extension projecting from the mold 85 board, a rod constructed in sections and secured to the mold board extension and to a rigid portion of the plow, respectively, the adjacent ends of said sections being oppositely threaded, a threaded sleeve encircling 90 said ends and adapted to move them towards or away from each other, whereby to extend or contract the rod, and a similarly constructed brace secured at one end to the mold board and formed at its opposite end with an 95 eye encircling said rod.

In testimony whereof I affix my signature in presence of two witnesses.

ABRAM L. COVEY. [L. s.]
